PICKUP ARM FOR PHONOGRAHS

Donald J. Baker, Los Angeles, Calif.

Application January 9, 1948, Serial No. 1,399

5 Claims. (Cl. 274—23)

1

This invention relates to pickup arms for electric phonographs.

A broad object of the invention is to devise a pickup arm structure in which some of the weight of the arm and the attached pickup is counterbalanced by means of a spring element enclosed within the arm.

Another object is to devise a structure in which the counterbalancing spring cooperates with the enclosing arm to form a friction brake to damp out any resonant effects which may otherwise develop in the arm itself or in the spring.

Other objects will become apparent from the following description of the invention.

The preferred form of the invention is illustrated in the accompanying drawing in which:

Figure 1 is a plan view of the pickup arm;

Figure 2 is an elevational view of Figure 1 showing part of the pickup head and the forward end of the arm in section, and the arrangement for pivotally mounting the rear end of the arm is also shown in section; and

Figure 3 is a side elevational view of the arrangement for pivotally supporting the rear end of the arm.

Referring to the drawing, 1 indicates the baseboard for supporting the usual turntable 2 carrying a record 3 which is engaged by the stylus of the pickup head 4 carried by a tubular arm 5. The pickup head is secured to the free end of the arm 5 by means of a screw 6 passing vertically through the forward end of the tube and being threaded into the lower removable part of the casing of pickup head 4.

The rear end of the arm 5 is secured to a hollow casing 7 which is pivotally mounted to permit the arm 5 to be moved in any direction about both a horizontal axis and a vertical axis. The rear end of arm 5 enters a bore formed in the front wall of casing 7, and the wall portion 7a below the bore is slotted in a vertical plane. A clamping screw 7b passing through the slotted wall portion clamps the end of arm 5 in the bore.

The arrangement for supporting the casing 7 for swinging movement about a vertical axis involves a vertical pivot tube 8 journaled in a sleeve 9 which is secured to the baseboard 1 by a nut 10. The upper end of sleeve 8 carries a U-shaped bracket 11, and casing 7 is pivotally supported on the bracket 11 by means of a horizontal pivot pin 12 passing through the casing 7 and through the upstanding arms of the bracket 11. Bracket 11 is mounted on the upper end of tube 8 in the manner shown in Figure 2, that is, the upper end of tube 8 has a reduced portion which enters a hole formed in the yoke

2

section of the U-shaped bracket, and the outer end of the reduced portion of tube 8 is turned over or flared outwardly to rivet the bracket to the tube. By means of the arrangement just described, the arm 5 may be swung horizontally about a vertical axis provided by sleeve 8, and may be swung vertically about a horizontal axis provided by pivot pin 12. Casing 7 is provided with an abutment 7c arranged in spaced relation

10 with an abutment 11a carried on one or both arms of the bracket 11 to limit the downward movement of the arm 5. As shown in Figure 2, these abutments are normally spaced apart when the pickup is in operative engagement with the record on the turntable, and the spacing of the abutments is sufficiently close to prevent the stylus of the pickup from engaging the baseboard 1 when the pickup is lowered beyond the outer edge of the turntable.

15 The counterbalancing spring 13 is arranged within the tubular arm 5 and is connected at its forward end to the screw 6. The rear end of the spring 13 is connected to a flexible cable or string 14 which passes rearwardly over a pulley 15 journaled on an axle 15a within the casing 7. The cable 14 is provided with a loop 14a at its rear end which engages a hook portion of an anchor element 16 removably secured to the end of a rearwardly extending arm 11b of bracket 11.

20 The spring 13 is under tension when mounted as shown in Figure 2, and the arrangement is such that the pull of the spring on the bracket arm 11b tends to counterbalance the weight of the arm, and thereby reduces the pressure of the stylus on the record. By properly designing the spring and its connections, the pressure of the stylus on the record can be fixed at any desired value.

As shown in Figure 1, the tubular arm 5 is bent 25 in a reverse curve in the horizontal plane. By this curved arrangement, the longitudinal axis of the pickup head 4 is properly oriented with respect to the radius of the record 3 at the point where the stylus engages the record. Also, the

30 curved form of the arm 5 causes the spring 13 to frictionally engage the walls of the arm on one side in the zone 5a and on the other side in the zone 5b, see Figure 1. The frictional engagement of the spring against the sides of tube 5 serves to damp out any resonance effect which may be inherent in the arm itself. Also, it serves to damp out any local vibration which might otherwise be set up within the spring itself. It will be understood that the same damping action will be secured with a single bend in the arm 5 and a reverse bend is not essential.

35 Casing 7 is provided with an internal abut-

ment 7d arranged to engage the rear end of the rearwardly extending arm 11b of bracket 11 to limit the extent of vertical swing of the arm 5 about the axis 12. For example, abutment 7d is normally spaced from the arm 11b by a distance which would permit the arm to swing vertically through an angle of about 15° before the abutment comes in contact with the arm 11b. The counterbalancing spring 13 preferably extends substantially throughout the length of the arm 5 so that the amount of shortening of the spring when the pickup arm is raised from the record is relatively small, with the result that the counterbalancing force exerted by the spring remains substantially constant in all vertical positions of the pickup arm.

A pair of connecting leads 17 for the pickup 4 extends rearwardly through the spring 13 in the arm 5 into the hollow casing 7 and then vertically downward through the pivot tube 8 to the usual amplifier not shown. With this arrangement, the connecting leads 17 are shielded throughout their length by the pickup arm assembly, and these leads may be formed of unshielded conductors up to the point where they emerge from the sleeve 8.

The pull of spring 13 on the forward end of arm 5 is along the axis of tube 5 which passes above the horizontal pivotal axis 12 and thereby exerts a counterbalancing pull on the arm. The pulley 15 could be omitted if the arm 11b were extended upwardly and rearwardly to a point approximately where the cable 14 engages the pulley.

I claim:

1. In a pickup arm for phonographs, the combination of a tubular arm supporting a pickup at one end and rigidly secured to a hollow casing at the other end, a pivot pin mounted for turning on a vertical axis, means mounting said casing on said pivot pin for swinging movement about said vertical axis and for pivotal movement about a horizontal axis, an arm rigidly secured to said pivot pin within said casing and extending rearwardly from said pin, a coiled spring located within said tubular arm between said casing and said pickup and having its forward end secured to said tubular arm, an idler pulley journaled in said casing, and a flexible connection extending from the rear end of said spring and passing over said pulley and being connected to said rearwardly extending arm for maintaining said spring under tension, said connection passing into said casing above said horizontal axis whereby the pull of said spring counterbalances part of the weight of said pickup arm.

2. A pickup arm assembly comprising a tubular arm pivotally mounted at one end and adapted to carry a pickup head on the other end, a coiled spring within said arm and maintained under tension, said arm being curved in a horizontal plane to cause frictional engagement of said spring with the wall of said arm over a substantial portion of the length of said arm whereby the frictional engagement between said spring and the wall of said arm damps out resonant effects within said arm.

3. A pickup arm assembly comprising a tubular arm adapted to carry a pickup head on one end, pivotal means at the other end of said arm for supporting the arm for swinging about a vertical axis a coiled spring within said arm, means attaching one end of said spring to the free end of said arm, means securing the other

end of said spring under tension to said pivotal means to counterbalance part of the weight of said arm, said arm being curved in a horizontal plane to cause engagement of said spring with the wall of said arm over a substantial portion of the length of said arm, whereby resonant effects within said arm will be damped out.

4. A pickup arm for phonographs comprising a U-shaped bracket pivotally mounted for rotation about a vertical axis, said bracket having a rearwardly extending arm formed thereon, a hollow casing pivotally mounted on said U-shaped bracket by means of a horizontally disposed pin passing through said casing and through the legs of said bracket, a reversely-curved tubular arm having one end mounted in said casing at a point above said horizontally disposed pin, a pulley mounted for rotation in a vertical plane within said casing and in alignment with said tubular arm, a pickup head mounted on the other end of said tubular arm by means of a single screw extending transversely through said tubular arm, a tensioned coil spring disposed internally of said tubular arm and having one end attached to said transverse screw, and a flexible cable attached to the other end of said spring, said cable extending over said pulley and being attached to said rearwardly extending arm of said U-shaped bracket, whereby said spring will counterbalance part of the weight of said pickup arm and tends to damp out resonance effects within said arm by frictional contact with the walls of said arm.

5. In a pickup arm for phonographs, the combination of a tubular arm supporting a pickup at one end and rigidly secured to a hollow casing at the other end, a pivot pin mounted for turning on a vertical axis, means mounting said casing on said pivot pin for swinging movement about said vertical axis and for pivotal movement about a horizontal axis, an arm rigidly secured to said pivot pin within said casing and extending rearwardly from said pin, a coiled spring located within said tubular arm between said casing and said pickup and having its forward end secured to said tubular arm, and a connection from the rear end of said spring to said rearwardly extending arm for maintaining said spring under tension, said connection passing into said casing above said horizontal axis whereby the pull of said spring counterbalances part of the weight of said pickup arm, said tubular arm being curved in a horizontal plane to cause said spring to have frictional contact with the wall of said tubular arm.

DONALD J. BAKER.
